(57) **CLAIM**

I claim the ornamental design for a flexible handle, as shown and described.

DESCRIPTION

FIG. 1 is a rear elevational view of a flexible handle incorporating my new design;

FIG. 2 is a bottom plan view thereof, the top view being a mirror image thereof;

FIG. 3 is a right side elevational view thereof, the left side being a mirror image thereof;

FIG. 4 is a front elevational view thereof;

FIG. 5 is a cross sectional view taken along line 5—5 in FIG. 1;

FIG. 6 is a rear elevational view of a second embodiment of the handle shown in FIG. 1;

FIG. 7 is a bottom plan view thereof, the top view being a mirror image thereof;

FIG. 8 is a left side elevational view thereof, the right side being a mirror image thereof;

FIG. 9 is a front elevational view thereof; and,

FIG. 10 is a cross sectional view taken along line 10—10 in FIG. 6.
